UNITED STATES PATENT OFFICE.

JACOB H. WEISBROD AND PAUL M. BEARD, OF ST. LOUIS, MISSOURI, ASSIGNORS TO AMERICAN CAR AND FOUNDRY COMPANY, OF ST. LOUIS, MISSOURI, A CORPORATION OF NEW JERSEY.

RAILWAY-CAR UNDERFRAME.

1,199,845.

Specification of Letters Patent.

Patented Oct. 3, 1916.

Application filed October 5, 1915. Serial No. 54,182.

To all whom it may concern:

Be it known that we, JACOB H. WEISBROD and PAUL M. BEARD, residing at St. Louis, Missouri, and being citizens of the 5 United States, have invented certain new and useful Improvements in Railway-Car Underframes, of which the following is a full, clear, and exact description, such as will enable others skilled in the art to which 10 it appertains to make and to use the same, reference being had to the accompanying drawings, which illustrate the preferred form of the invention, though it is to be understood that the invention is not limited to 15 the exact details of construction shown and described, as it is obvious that various modifications thereof will occur to persons skilled in the art.

In said drawings: Figure 1 is a plan of 20 part of a sill. Fig. 2 is a side elevational view of the parts shown in Fig. 1. Fig. 3 is a sectional view the section being taken on line 3—3 of Fig. 2. Fig. 4 is a broken sectional view the section being taken trans- 25 versely through the top member of our center sill.

The invention relates to improvements in 30 railway car underframes and is intended to facilitate the operation of assembling the parts thereof thereby effecting great economy in the cost of labor employed and, at the same time producing a structure possessing many material advantages over other structures of the same class.

The object of this invention is to provide 35 an efficient railway car underframe of structural shapes adapted to facilitate erection and to reduce to a minimum the cost of labor incident thereto.

Underframes of structural shapes are 40 easily adapted to different conditions and strength requirements. The majority of commercial shapes, however, are designed with scant regard to the requirements of 45 railway construction, this being especially true of such shapes as are desirable for use in center sills. These sills usually consist of web plates, top and bottom chords on both sides of the web, and a cover plate for 50 top or bottom or both. Such construction necessitates the handling, punching and riv-

eting of several more members than are involved in the present sill construction.

Other advantages appear in the description and drawings.

The center sill construction comprises spaced web portions 1; bottom chords 2, and a combined center sill cover plate and top chord 3, with associated parts hereinafter described. The bottom chords 2, are preferably of inverted T-shape in cross section as best shown in Fig. 3. Their vertical legs 5, and inturned horizontal legs 6, are preferably relatively thin while the outstanding legs 7 are relatively thick, the thinner legs 60 being so formed to provide metal of such thickness that it may be conveniently perforated in the commonly used punching machines and the thicker legs 7, being especially adapted to resist buckling stresses in 70 the sills.

Ordinary rolled commercial T-sections have sloping flanges which make them undesirable as chord members in sill construction, and such commercial T-sections as are 75 readily obtainable in the open market, of sufficient section for use as chord members in such construction, are of substantially uniform section in all of their flanges, thus making the punching of such flanges a difficult and expensive undertaking.

T-sections of the sectional contour disclosed in the drawings permit the elimination of one member and one row of punched holes while securing a bottom chord member 85 in a center sill substantially equal in value to two commercial angles such as have heretofore been employed.

It is to be noted that the flanges 5 and 6 are substantially flat throughout the greater 90 portion of their area and afford ready connection to sill webs and the pieces secured thereto. The top chord 3 of the sill is of double channel form in the preferred section shown in Fig. 3 in which 8 is the relatively thick web portion, 9—9 a pair of offset substantially horizontal flanges formed as extensions of the web but preferably thinner and rising to a higher plane (when positioned as shown) to which flanges 9 floor 95 boards 10 are bolted as shown in Fig. 3 leaving a clear space 11 between the web 8 and

the bottom of such boards for drainage, etc., thereby preventing rotting of the boards.

Formed integral with the web 8 and flanges 9 are vertically disposed parallel flanges 12 which, in the sill construction illustrated, extend parallel with the spaced webs 1 of said sills and are secured thereto by the rows of rivets 13, while the offset flanges 9 overlap the upper edges of said webs. Secured to the webs 1 by the rivets 13 are longitudinally extending angles 15 which, with the similarly disposed angles 16, are secured respectively to the top and bottom flanges 17 and 18 of the cross bearers 15 which latter project through coincident openings in the spaced webs of the center sill, and the webs 19 of said cross bearers are connected to the upper ends of offset angles 20 by rivets 21, while rivets 22 secure the lower portions of the angles 20 to the webs 1.

The offset angles 20 provide rigid braces for the cross bearers in the planes of the angles 15 and 16 and both may be used without interference of one with the other in assembling the parts.

To spread and stiffen the sills the box pressing 25 or an equivalent casting is preferably employed as shown, through the flanges 26 of which rivets 22 pass to secure said member in position in alignment with the flanges 20^a of the braces 20 before referred to.

In the preferred construction the top chord extends over and beyond the bolsters 35 B at each end of the car and the bottom chords extend through said bolsters all as shown in Fig. 2 though it is evident that the top and bottom chords, one or all, may be longer or shorter as may be desired.

40 The modification disclosed in sectional detail in Fig. 4 possesses the advantage of a thicker web portion 8' which may be employed when metal flooring is used in the car.

45 What we claim is:

1. In combination in a car underframe, a pair of spaced plate girder center sills the web of each of which is perforated, a cross bearer projected through said perforations, 50 reinforce members connecting the cross bearer to the webs of said sills, and connection members secured to said sills and cross bearers intermediate the webs of said sills and the reinforce members.

55 2. In combination in a car underframe, spaced center sills having perforated webs, a cross bearer extending through said webs, longitudinally extending members connected to said sill webs and to said cross bearer, 60 and connection members secured to said sill webs and to the web of said cross bearer in the zone of said longitudinally extending members.

3. In combination in a car underframe, a 65 center sill construction comprising spaced

web portions, inverted T-shaped bottom chords connected thereto and an integral sill cover plate of inverted channel form having outstanding flanges overlapping the said web portions.

4. In combination in a car underframe, a center sill construction comprising spaced web portions, angularly disposed members secured to each of said webs, cross bearers projected through said webs and resting 75 above some of said members and being secured to others of said members at a distance from said webs.

5. In combination in a car underframe, a center sill construction comprising spaced 80 webs, flanged members connected to said webs and extending longitudinally thereof, cross bearers extending through said webs and being secured to said flanged members, and braces connecting said webs and said 85 cross bearers.

6. In a center sill construction, spaced webs, tension chords and a top cover plate overlapping said webs and comprising a top and a bottom channel portion the flanges of 90 the bottom channel portion being secured to said spaced webs.

7. In a center sill construction, spaced webs and a connecting cover plate secured thereto said cover plate comprising vertical 95 and horizontal flanges and a central channel portion.

8. In a center sill construction, spaced webs and a connecting cover plate secured thereto said cover plate comprising vertical 100 and horizontal flanges and a plurality of central channel portions.

9. In combination in a car, a center sill comprising a unitary sill cover plate of channel form in cross section adapted for 105 connection, through some of its flanges, to floor boards which rest in surface contact with said flanges while the portion of said cover plate intermediate said flanges is spaced from said floor boards.

10. In combination in a car, a center sill cover plate provided at each side with a horizontal flange and a vertical flange and an intermediate web portion forming with 110 said flanges a plural channel, webs connected to said vertical flanges and a floor connected to said horizontal flanges said floor being spaced from said web portion.

11. In combination in a car underframe, a plurality of sill webs, a cross member extending therethrough, angles extending longitudinally of the webs and adapted to support said cross member, a compression filler between the lower parts of said webs, and a rolled member overlapping and paralleling 125 said webs and being connected to the upper portions thereof.

12. In combination in a car underframe, spaced sill webs, and a top cover plate connecting said webs, said cover plate in part 130

- paralleling said webs and in part overlapping said webs and a flanged filler interposed between the lower portion of said webs and connected thereto.
- 5 13. In combination in a car underframe, a center sill construction comprising spaced web plates, longitudinally extending angles attached to each plate, a cross bearer penetrating said webs and being connected to 10 said angles, obliquely extending braces connected to the webs of said sills and to the said cross bearers, a cover plate connected to said web plates and to some of said angles, and a filler interposed between the 15 lower portions of said spaced web plates.
14. In combination in a car underframe, spaced center sill webs, a cross bearer extending continuously through coincident openings in said webs, longitudinally extending web stiffening members secured thereto, cross bearers extending through said webs and connected to said stiffening members, offset braces connecting said sill webs and said cross bearer and a center sill cover 25 plate connecting said sill webs.
15. As an article of manufacture, an integral rolled member comprising a web portion terminating in relatively thin offset flanges and being provided with a thicker 30 web portion and intermediate angularly disposed flanges said mentioned flanges being respectively adapted to overlap and parallel spaced web plates of a girder.
16. In combination in a car underframe, a center sill construction comprising spaced web portions, inverted T-shaped bottom chord members having relatively thin vertical legs lapping and being secured to said web portions and having relatively thick 35 outstanding bottom flanges and means connecting the upper portions of said spaced web portions.
17. In combination in a car sill construction, spaced vertical webs, means connecting said webs, chord members lapping said webs, said chord members having relatively thick portions extending at an angle to said webs and relatively thin portions lapping and being secured to said webs.
18. In combination in a car sill construction, spaced vertical webs, means penetrating and connecting said webs intermediate their top and bottom edges, chord members lapping said webs, said chord members having relatively thick portions extending at 40 45 50 55 an angle to said webs and relatively thin portions lapping and being secured to said webs.

In witness whereof we have hereunto set our hands in the presence of two witnesses. 60

JACOB H. WEISBROD.
PAUL M. BEARD.
